UNITED STATES PATENT OFFICE.

ROBERT WILLIAM HAMPSON, OF WATERBURY, CONNECTICUT.

CIGAR HOLDER AND ASH RECEIVER.

Application filed October 3, 1924. Serial No. 741,334.

To all whom it may concern:

Be it known that I, ROBERT WILLIAM HAMPSON, a citizen of the United States, and a resident of Waterbury, county of New Haven, and State of Connecticut, have invented certain new and useful Improvements in Cigar Holders and Ash Receivers, of which the following is a specification.

This invention relates to smokers' accessories, and more particularly to a device for temporarily holding lighted cigars and cigarettes when not being smoked.

One object of this invention is to produce a device of the above nature, having a tray to receive partly burned matches and any ashes which may drop from the cigars and cigarettes.

A further object of this invention is to provide a holder and tray of the above nature adapted to hold a cigar vertically with its lighted end down, and to partly confine the heat of said lighted end.

A further object is to provide a cigar holder adapted to receive cigars of any diameter, and which will keep them lighted for the longest possible time while out of the smoker's mouth.

A further object is to provide a cigar holder in which air is supplied underneath the lighted end of the cigar so as to produce a draft to accelerate the combustion thereof.

A further object is to provide a device of the above nature which will be simple and compact in construction, sanitary, easy to manipulate, attractive in appearance, inexpensive to manufacture, and very efficient and durable in use.

With these and other objects in view there has been illustrated on the accompanying drawing one form in which the invention may be conveniently embodied in practice.

Fig. 1 represents a vertical sectional view of the combined cigar and cigarette holder and ash receiver.

Fig. 2 is a top plan view of the same.

Fig. 3 is a perspective view of a supporting stand on which four of the cigar holders have been installed.

The former types of cigar holders which supported the cigar horizontally were unsatisfactory on account of the fact that in this position a lighted cigar soon becomes extin-

guished. Besides causing the cigar to become stale and producing objectionable tastes and odors, the smoker was put to the trouble of relighting the cigar. By means of the present invention, the above and other disadvantages have been avoided.

Referring now to the drawings in which like reference numerals denote corresponding parts throughout the several views, the numeral 10 indicates a cylindrical container having flat top and bottom portions 11 and 12 respectively. The top portion 11 has a V-shaped slot 13 extending inwardly from one edge for a distance equal to about three-quarters of the diameter thereof, said slot 13 having a curved apex 14, as most clearly shown in Fig. 2.

The cylindrical portion of the container is provided with a U-shaped slot 15 extending downwardly from the top portion 11 for a distance equal to about two-thirds of the height of the container. The U-shaped slot 15 has parallel side edges 16 and 17 which are adapted to align with the ends of the V-shaped slot 13.

At the bottom 18 of the U-shaped slot 15, the metal of the container is bent outwardly and curved to form a cigarette shelf 19, said shelf being concave upwardly and shaped to fit the contour of a cigarette.

When a smoker desires to lay aside his cigar temporarily, he will move it with its lighted end down in a vertical position laterally through the U-slot 15 until it comes into engagement with the side edges of the V-slot 13. The cigar will thus be slightly compressed and will be held in said V-slot with its lighted end within the lower part of the container 10. The heat generated by the combustion of the cigar will thus be confined, which will tend to prevent rapid cooling off of the cigar. Moreover, the hot gases from the burning end 21 of the cigar will rise vertically upward and will warm the portion of the cigar next above, thus accelerating the combustion, and also tending to retard the cooling off of the cigar. The rate of combustion will also be increased by reason of the natural draft of air which will flow through the U-slot up around the cigar.

It will thus be seen that the cigar will be held in the container in a position which

imitates so far as possible the position in which an experienced smoker would naturally hold the cigar in his hand when not puffing it.

6. A lighted cigarette 22 may also be laid horizontally upon the shelf 19, and the ashes falling both from the cigar 20 and cigarette 22 will be received in the bottom of the container 10.

10. Fig. 3 discloses a plurality of cigar-holding units assembled on arms 23 radiating from a central post 24, said post being mounted on a rectangular stand 25 adapted to rest upon a table, desk, or other support.

15. A handle 26 is also provided at the top of said post 24 in order to permit the stand to be readily moved about.

One advantage of this invention is that ashes and other refuse which may be in the 20 bottom of the container will be hidden from view, but may be easily emptied from said container whenever desired.

A further advantage is that by supporting the cigar in a vertical position, the unlighted 25 end thereof will be out of contact with any supporting surface which might be likely to contaminate it.

A still further advantage is that the lighted end of the cigar is kept well inside 30 of the container, thus reducing the danger of accidentally setting fire to surrounding objects.

While there has been disclosed in this 35 specification one form in which the invention may be embodied, it is to be understood that this form is shown for the purpose of illustration only, and that the invention is not to be limited to the specific disclosure but may be modified and embodied in various other forms without departing from 40 its spirit. In short, the invention includes all the modifications and embodiments coming within the scope of the following claims.

Having thus fully described the invention, 45 what is claimed as new, and for which it is desired to secure Letters Patent, is:

1. In a combined cigar holder and ash tray, a receptacle having means at the upper portion thereof to receive the intermediate 50 portion of a cigar for holding the same vertically, said receptacle also having a side opening to permit the lateral movement of a vertical cigar into engagement with said means.

55. 2. In a combined cigar holder and ash tray, a receptacle having a cover, said cover having a wedge slot extending thereinto to receive the intermediate portion of a cigar for holding the same vertically, said receptacle also having a side opening communicating with said slot to permit the lateral movement of a vertical cigar into engagement with said slot.

60. 3. In a combined cigar holder and ash receiver, a cylindrical container having a

flat top, said top having a wedge-shaped slot extending thereinto to receive cigars of various diameters for holding them in vertical position, said container having an opening in its side in alinement with said wedge-shaped slot to permit a vertical cigar to be moved horizontally into engagement with said wedge-shaped slot.

4. In a combined cigar holder and ash tray, a receptacle having a flat disc supported above its base, said disc having an opening in its side with inclined edges to receive the intermediate portion of a cigar for holding the same vertically, said receptacle also having a vertical side slot communicating with said disc-opening to permit the lateral movement of a vertical cigar into engagement with said disc-opening.

5. In a combined cigar holder and ash receiver, a cylindrical container having a flat cover member, said member having a wedge-shaped slot extending into one edge thereof to receive cigars of various diameters for holding them in vertical position, said container having a U-shaped opening in its side in alinement with the ends of said slot, whereby a cigar held in vertical position may be moved laterally into engagement with said wedge-shaped slot.

6. In a combined cigar holder and ash receiver, a cylindrical container having a flat cover member, said member having a wedge-shaped slot extending thereinto to receive cigars of various diameters for holding them in vertical position, said container having an opening in its side in alinement with said slot, whereby a cigar held in a vertical position may be moved laterally into and out of engagement with said slot, and a horizontal cigarette-holding shelf 100 projecting out from the bottom of said side opening.

7. In a combination cigar holder and ash receiver, a cigar supporting member having a laterally extending slot with inclined edges extending thereinto to receive a cigar and hold it with its lighted end downwardly, and means below said supporting member to receive the ashes from said cigar, said cigar being located with its lighted end well within said ash receiving means.

8. In a combined cigar holder and ash receiver, a receptacle, said receptacle having a cover, said cover having an opening in which a cigar may be supported in vertical position, said receptacle having an opening below said cover to permit the entrance of air to cause a natural draft of air up around said cigar, said cigar being located with its lighted end well within said receptacle, the ashes from said cigar being received in the receptacle below said cover.

9. In a combined cigar holder and ash receiver, an ash receptacle, means in said receptacle for supporting a cigar with its

lighted end down whereby the unlighted end will be kept out of contact with contaminating surfaces, and with the lighted end of said cigar located well within said receptacle, whereby danger of accidentally setting fire to surrounding objects will be avoided, said receptacle having a ventila-

tion opening in its side to permit a draft of heated air to circulate up around said cigar to promote the combustion thereof. 10

In testimony whereof, I have affixed my signature to this specification.

ROBERT WILLIAM HAMPSON.
